UNITED STATES PATENT OFFICE.

CLAYFORD T. GRIMM, OF ADRIAN, WEST VIRGINIA.

TIE-PLATE.

1,343,262.

Specification of Letters Patent. Patented June 15, 1920.

Application filed April 2, 1920. Serial No. 370,804.

To all whom it may concern:

Be it known that I, CLAYFORD T. GRIMM, a citizen of the United States, residing at Adrian, in the county of Upshur and State 5 of West Virginia, have invented certain new and useful Improvements in Tie-Plates; and I do hereby declare the following to be full, clear, and exact description of the same, reference being had to the accompanying drawings, forming part of this specification.

This invention relates to a means commonly known as a tie plate for holding in proper position the rails of a more or less temporary track and has particular application to tie plates for use in mines.

The objects of the present invention are: first, to provide a perfectly satisfactory tie plate; second, to provide a tie plate that can be manufactured for a less sum than any 20 other tie plate on the market; and third, to provide a tie plate which will not shift position but will afford a firm purchase into the pavement, the latter term being used to denote the solid hard ground in the mine on 25 which the track is laid. There are a number of tie plates on the market and at least three of these are in quite general use and give a fair measure of satisfaction, but each has its own inherent defect, for example, 30 one of the most satisfactory tie rods on the market gives service in every way except that when the mule pulling the car kicks against the tie, the kick will shift the tie with respect to the rails. This happens with 35 aggravating frequency and the present invention was originated in order to overcome this feature. Another popular tie rod in mine use is objectionable in that while the tie is fairly serviceable, it is practically impossible to disassemble the device within a reasonable time when it is desired to shift 40 the track to a different location. The present invention was made with the thought in mind that removability is an essential element and must be provided for. Still another popular tie rod in mine use is not only 45 very expensive, but after some length of service tends to open up at the extreme ends which necessitates the taking of the rod to the blacksmith shop for repairs at altogether 50 too frequent intervals. The stress and opening up of the ends is avoided in the tie plate described herein in that the entire bottom of

the plate, except for the prong on each clamp, is flush with the pavement.

55

Referring now to the drawings forming part of this specification:

Figure 1 represents an elevation of my device but broken away to one side to show the parts in cross section.

60

Fig. 2 is a bottom plan view of my device, but with the right hand clamp omitted.

Fig. 3 is a top plan view showing a rail on the right hand side, but omitting it on the left hand side for clearness.

65

Fig. 4 is a side elevation of my preferred form of clamp.

Fig. 5 is a plan view thereof.

Fig. 6 is a plan view of a modified form of clamp.

70

Fig. 7 is a side elevation of such modification.

My tie 10 is formed of channel iron having the usual flanges 11 and 12 and being turned up at either end as at 14 to form a recess 15 adapted to fairly well fit the outer flange 16 of an ordinary rail 17 usually of about sixteen to twenty pounds weight as is customary in mine work. The tie 10 is provided at either end near the turned up portion 14 with a hole either circular as shown at 18 or square as shown at 19 and is further provided between such hole and the recess 15 with an orifice 20 preferably arch shape as shown in the various figures, but 85 which may of course be oblong or any other shape desired, the purpose of this orifice being to receive the jaw 21 of the clamp 22.

In all of the modifications shown the clamp 22 is an integral piece consisting of 90 the body, jaw, and the prong, and in most of the modifications *i. e.*, all except the one shown at the left of Fig. 2, also having an integral lug for holding the clamp in proper position on the tie. In the preferred form 95 the jaw 21 is fashioned so as to ride over the inner flange 23 of the rail 17 and having a vertical face 24 adapted to abut the web of such rail; such jaw 21 being approximately the size of the orifice 20 and may if desired 100 be nearly as large in cross sectional area as the body of the clamp itself, or it may be merely stamped from a relatively heavy sheet of metal in which case the thickness of the abutting face 24 would be the same as 105 the thickness of the body 22, that is, the

depth of the channel flanges. The prong 25 is best seen in Fig. 2 and consists of a pointed end of the flange bent at right angles and adapted to be firmly pressed into the mine pavement to hold the device in place.

The lug 26 is perforated to receive a holding means which may be a cotter pin 27 having an eye sufficiently large to receive the point of a pick, or the fastening means 10 may consist of a wedge 28 adapted to be driven in as far as it will go and then secured in place by a slight tap on the pointed end which will bend the wedge as shown at 15 29 effectively preventing it from coming loose. The lug 26 is an integral part of the clamp and may be either drawn up from the metal or it may be a separate piece welded thereto, but it is preferably struck up from the metal as clearly shown in Figs. 4 and 5, 20 the principal advantage of this being cheapness in manufacture.

In Fig. 2 on the left hand side I have shown the clamp and tie plate each provided with a circular hole to permit the use of an 25 ordinary bolt which it is intended to apply in the usual way, that is, with the head down and the nut, indicated in dotted lines, on the upper surface for convenience in operation. I do not intend to use a nut and bolt in securing my clamps to the tie plates but have 30 illustrated this form, in order to show that my device is not limited to the exact structure shown in any particular figure, but it is to be limited only as called for in the 35 claims hereinafter.

In the modification shown in Figs. 6 and 7 the jaw may be exactly as shown in Figs. 4 and 5 or it may consist in a stamped out restricted portion 30, and may if desired 40 have two small prongs 31 shown in dotted lines to aid in holding the tie in place. The real modification, however, of the clamp as shown in these figures consists in slitting the body 22^a as shown at 33 and 34 thus providing 45 two prongs 35 and between them a lug 36 perforated as at 37 to receive the cotter pin or wedge. This modification differs from the preferred form in that there are two prongs and that these prongs are nearer 50 to the rail than is the lug 36 which is just the reverse of the case in the preferred form. It is necessary that the prongs and lugs shall not be in vertical alinement in order to facilitate the driving of the prong or prongs

into the pavement which is not always an 55 easy task, the pavements at times being very hard.

It is believed that the operation is now clear. The tie plates are laid loosely on the ground in proper position and the rails are 60 then driven firmly into the recesses 15. The clamp 22 is now put in place by lifting the rails and ties and by pushing the jaw 21 up through the orifice 20 and then bringing the lug 26 through the hole 19 which is sufficiently 65 large to permit the arc movement. The cotter or wedge is now driven through the perforation in the lug which holds the clamp in position on the channel bar with the lower surface of the body of the clamp 70 flush with the lower margin of the channel bar flanges. Now all that remains to do is to drive the prongs into the pavement which act is performed with any convenient and suitable tool, usually with a pick, but a hammer or sledge should be used if at hand. If 75 wedges are used they are now given an additional tap to more firmly secure the rail to the plate and then the wedges are bent to prevent their coming loose. 80

What I claim is:—

1. In a device of the character described, a tie fashioned from a strip of channel iron and bent at either end to form a recess to receive a rail, said channel iron having a hole 85 near each end and an orifice of larger size than said hole between said hole and said recess, a clamp member having an integral upturned jaw and an integral downturned prong, said jaw adapted to pass through 90 said orifice and to hold said rail in said recess, and means adapted to pass through said hole to secure said clamp to said tie.

2. A clamp plate for use with a metal tie consisting of a single piece having an upturned jaw a downturned prong and an integral lug adapted to receive a fastening means for securing said clamp to said tie. 95

3. A clamp adapted for use with a metal tie for temporary railway use, said clamp 100 consisting of a body having an integral upturned jaw at one end adapted to abut a rail and hold the same in place on said tie and having at the other end a downturned prong adapted to be inserted in the ground in 105 order to hold said clamp and tie in proper position.

CLAYFORD T. GRIMM.
